UNITED STATES PATENT OFFICE

91,822

DESIGN FOR A BEER DISPENSING CABINET

Charles Harazen, Chicago, and Frank J. Hajek, Riverside, Ill.

Application December 30, 1933, Serial No. 50,274

Term of patent 7 years

To all whom it may concern:

Be it known that we, CHARLES HARAZEN, a citizen of the United States, residing at Chicago, in the county of Cook and State of Illinois, and FRANK J. HAJEK, a citizen of the United States, residing at the village of Riverside, in the county of Cook and State of Illinois, have invented a new, original, and ornamental Design for a Beer Dispensing Cabinet, of which the following is a specification, reference being had to the accompanying drawing forming a part thereof.

The drawing is a perspective view of the cabinet showing our new design.

We claim:

The ornamental design for a beer dispensing cabinet substantially as shown.

CHARLES HARAZEN.
FRANK J. HAJEK.
